UNITED STATES PATENT OFFICE.

ARTHUR H. HUDSON, OF SALT LAKE CITY, UTAH.

REVOLVER-HOLSTER.

No. 902,083.

Specification of Letters Patent.

Patented Oct. 27, 1908.

Application filed February 24, 1908. Serial No. 417,370.

To all whom it may concern:

Be it known that I, ARTHUR H. HUDSON, a citizen of the United States, residing at Salt Lake City, in the county of Salt Lake and State of Utah, have invented certain new and useful Improvements in Revolver-Holsters, of which the following is a specification.

My invention relates to housings or holders for fire arms such as revolvers and pistols and refers particularly to holsters adapted to be carried upon the person.

The chief objects of the improvements which form the subject matter of this application are:—to provide a casing or holder for the purpose stated that will permit of the instant extraction of the weapon therefrom; to furnish a holder for revolvers that will occupy a small space and be lightly constructed in order that it may be convenient to carry, and to supply a holster for a weapon that will be simple in construction, and in which the operating mechanism for delivering the arm will be conveniently reached for operating.

A further object of this invention is to provide an auxiliary member adapted to form a connection between the holster and the butt or handle of a pistol, whereby the holster may be used as a shoulder rest for the purpose of steadyng the weapon and thus increase the accuracy of the fire.

I accomplish the above results by the employment of the devices illustrated in the accompanying drawing forming a part of this application, the details of construction being disclosed in the following views.

Figure 1 is a front elevation of a preferred form of holster, only a portion of the suspending strap being shown; Figs. 2 and 3 are, respectively, rear and end elevations of the holster; Fig. 4 is a section on the line 4—4 of Fig. 1; Fig. 5 is a section on the line 5—5 of Fig. 2; Fig. 6 is a reduced side elevation of the holster attached to a revolver by the auxiliary member, and Fig. 7 is a fragmentary view in section of the lower portion of the holster illustrating the manner of securing the auxiliary member thereto.

Referring to the details of the drawing, the numeral 10 indicates the front wall and 11 the rear wall of a casing or holster, adapted to contain a revolver shown in dotted outlines at 12 in Fig. 1.

To supply the requisite rigidity to the structure I form the said walls of thin plates

13, 14. These plates are preferably formed of sheet metal of suitable gage, and are provided with ears 15, 16, formed integral with the said plates and bent at right angles therewith. These ears overlap when the plates are assembled, and are supplied with rivets 16^a serving as pivots upon which the plates mutually swing so that their lower margins may be separated in a manner hereinafter pointed out. Near the lower end the front plate 13 is supplied with integral lugs or ears 17, which project rearwardly and are then bent inwardly to form hooks or catches 18.

The lower corners of the back plate 14 are cut away, as shown at 19, to avoid interference with the catches 18, and across the lower part of said plate 14, upon the outer side, is mounted a transverse lever or latch 20, pivoted at its center to the said plate by a rivet 21. The ends of said lever are adapted to engage the hooks or catches 18 in the manner shown in Fig. 3. The outside face of the lever is supplied with a boss or lug 22 to afford a finger hold by means of which the lever may be readily swung upon its pivot to engage or disengage its ends from the catches 18. The lever 20 is made of spring metal of sufficient resiliency to insure its retention in any adjusted position. The ears 15, 16 are slightly separated from each other and upon the pivot therebetween is mounted, upon either side, a coiled spring 23, having its ends 24 extended and engaging holes in the opposite ears. The tendency of these springs is to keep the lower margins of the plates 13, 14 separated so that when the lever 20 is moved to release the catches 18 the plates will be quickly forced apart to permit the weapon concealed therein to fall into the operator's hand which is held below the holster. Both plates are preferably covered with some suitable material 25, and for this purpose I prefer leather or rubber fabric. The interior of the casing is supplied with a lining which may be similar to the material used for the covering. The upper opening of the holster is provided with a cover or flap 27 which may be formed of a separate piece or made continuous with the external and internal covers, as shown in the drawing. This flap may be secured by a button 28 or other suitable fastening. For supporting the holster upon the body of the user, I supply the usual straps 29 secured to the casing by passing

the ends through the wall plate 14 or in any preferred manner.

To afford a proper compartment for receiving the weapon the upper portion of the 5 front plate and one vertical margin are bent convexly, indicated in the drawing at 30. One of said ears 15 is extended downwardly to form an end plate 31. The lower margin of the front wall corresponding with 10 the convex part is bent towards the rear as at 32, to form a closure or floor for the convex portion of the housing when the walls are approximated, and to support the pistol, the muzzle of which rests thereon 15 when the casing is closed by the lever 20.

The holster being thus arranged and slung upon the shoulder of the wearer by means of the straps 19, the entire device may be concealed beneath the outer garment. When 20 the operator desires to release the weapon he places his finger upon the lug 22 and holds the hollow of his hand beneath the approximated lower margins of the casing walls. He then presses the lever 20 down 25 with the finger until it disengages the catches 18, when the walls will be instantly thrown apart by the action of the springs 23 and the weapon will fall by gravity through the opening thus formed and into the hand held 30 in readiness below.

In order to utilize the holster as a shoulder rest for the weapon, I provide an auxiliary member or attachment, consisting of a bar or arm 33, furnished with retaining lugs 34 near one end said lugs being adapted to engage holes 35 in the wall 10. The opposite end of the arm 33 is reduced at 36 to be received in a socket or mortise 37 formed in the handle of the revolver, a shoulder 38 40 serving as a stop for the handle. To assemble the parts thus described the spring lever 20 is released and the arm 33 inserted between the plates so that the lugs 34 will engage the holes 35. The plates are then 45 brought into apposition and locked by the lever 20, so that the arm 33 is firmly held between the casing walls. The revolver is then placed upon the reduced end 36 of the arm as shown in Fig. 6 where it is held by 50 friction, the said reduced portion being slightly tapered for that purpose.

Having thus described my invention what I claim is:—

1. A holster, comprising plates, spring

hinges connecting said plates near their 55 upper ends, and a manually operated latch adapted to lock said plates when in apposition.

2. A holster, including two plates arranged in apposition, ears attached to the 60 plates and pivotally connected to form hinges, springs for the hinges tending to separate said plates, and a latch pivoted to one of said plates and adapted to engage lugs upon the opposite plate. 65

3. In a holster for a pistol, the combination of a casing formed in sections, hinges connecting the sections near their upper 70 ends, springs for the hinges tending to separate said plates, and a latch pivoted to one of the plates and adapted to engage suitable lugs upon the opposite plate.

4. A holster for a pistol, including a casing composed of opposite plates, ears bent at right angle to the plates, to form the 75 ends of the casing, hinged connection between the ears, springs for the hinges, and a latch for locking the plates in apposition.

5. A holster for a pistol, including two plates arranged in apposition with each 80 other, pivotal connection between said plates, springs tending to separate the plates, means for locking the plates in apposition, and a removable arm adapted to be inserted between said plates and having 85 means for engaging one of said plates.

6. In a holster, the combination of a casing comprising two opposed plates, ears extending at a right angle from said plates and arranged to form ends for said casing, 90 pivots connecting the ears, springs tending to separate the plates, a latch for retaining the plates in apposition, and a cover for the casing.

7. In a holster, the combination of a casing comprising two plates hinged together, 95 springs tending to separate the plates, means for locking the plates in apposition, a removable arm adapted to be inserted between said plates, retaining means for the arm, 100 and a covering flap for the casing.

In testimony whereof I affix my signature in the presence of two witnesses.

ARTHUR H. HUDSON.
